UNITED STATES PATENT OFFICE

2,482,845

GRAIN CAR DOOR IMPLEMENT

Cornell Flagstad, Minneapolis, Minn.

Application August 14, 1944, Serial No. 549,467

3 Claims. (Cl. 254—131)

1

This invention relates to implements for removing the doors of the cars used by railroads for transporting grain.

Railroad cars for this purpose have wide doorways for loading and unloading grain and these doorways are closed during transport by means of doors which comprise several, relatively narrow door boards set on edge one above the other and nailed or otherwise secured at their ends to the inner surfaces of the posts defining said doorways. To unload the car the doors are removed one at a time, starting with the uppermost, and it is the common practice to pry the door loose by use of some kind of tool by which sufficient pressure may be exerted to force the door inwardly against the grain in the car. The door is then lifted and thrown over upon the grain, which runs out through the space thus provided. To my knowledge, however, no implement or tool has been provided which is particularly adapted for use in forcing the door inward in order to draw the nails from the post, and all such tools previously used have had the disadvantage that they in one way or another mar and damage both the post and the door.

It is the primary object of my invention, therefore, to provide an implement particularly adapted for cooperation with the ordinary grain car door and which may be readily engaged therewith and operated to exert the relatively considerable force needed to press the door inward against the pressure of the grain on its inner side. Another object is to provide an implement of this kind which may be selectively used at either end of the door with equal facility, and which is so constructed and arranged that the members actually contacting the door and the door posts will maintain an even bearing surface on these parts at all times, preventing injury to the wood.

These and other more detailed and specific objects will be disclosed in the course of the following specification, reference being had to the accompanying drawing, in which—

Fig. 1 is an outside elevation of a portion of the doorway of a grain car door and one of the doors used in connection therewith, showing my improved implement in operative position at one end of the door.

Fig. 2 is an enlarged side elevation, partially in section, of the operating end of the implement and with parts broken away to better disclose the interior construction.

Fig. 3 is an enlarged fragmentary vertical sectional view taken along the line 3—3 in Fig. 1 and

2

illustrating the operation of the implement in pressing the door inward away from the post.

Fig. 4 is a plan view of the implement in position for pressing the door inward away from the post and with the post itself shown in horizontal section.

Fig. 5 is a detailed sectional view taken along the line 5—5 in Fig. 2.

Referring now more particularly and by reference characters to the drawing, A designates a grain car door of conventional form arranged on edge in the doorway B of a grain car C and with its ends projecting beyond the margins of spaced upright door posts D, which define the lateral margins of the doorway B. The ends of the door A may be secured to inner surfaces of the post D in any conventional manner, such as by means of the nails indicated at E, it being here noted that only sufficient fastening is required to hold the door in place and against endwise displacement, inasmuch as the outward pressure of the grain in the car will, of course, hold the door tightly against the posts. As the filling of the car proceeds, other doors (not here shown) are arranged on edge above the door A until the doorway B is entirely closed.

To unload the car, the doors are then removed one at a time starting with the upper one, and to do this the doors must be forced inwardly against the pressure of the grain in a sufficient distance to draw the nails E from the posts D, whereupon the doors may be lifted up and thrown inwardly over and upon the grain which runs out through the space thus provided down to the level of the next door beneath.

In accordance with my invention, I provide an improved implement for accomplishing this first operation in prying the door inwardly. The second operation, that of lifting the door, may of course be carried out in any desired manner but I prefer to use for this purpose the implement disclosed in my co-pending application, Serial No. 532,296, filed April 22, 1944, now Patent No. 2,437,780, dated March 16, 1948.

My present implement is designated generally at F and comprises a handle 10 made up of an elongated bar 11 to one end of which are secured bracket plates 12 by means of rivets 13. The bracket plates 12 are fastened to opposite sides of the bar 11 and extend therebeyond for a considerable distance, being thus disposed in parallel spaced relation, as clearly indicated in Fig. 4. The bracket plates 12 are furthermore substantially triangular in shape and mounted at one upper corner of the plates is an upper member, design-

nated generally at 14, comprising a pair of L-shaped pieces 15 secured by welding or other suitable means to an elongated narrow plate 16 so that a pair of spaced ears 17 is provided and adapted to fit over opposite outer sides of the plates 12. The ears 17 are apertured to receive a rivet 18 which passes through the plates 12 and pivotally mounts the ears upon the handle with the plate 16 extending outwardly in opposite directions to each side forming laterally projecting hook or finger portions 19 adapted to selectively engage with inner sides of the door posts D as will be later described.

The lower corner of the plates carries another member, designated generally at 20, which is U-shaped in plan, having a flat bight portion 21 and spaced ears 22 adapted to fit over outer surfaces of the plates 12. These ears 22 are likewise apertured to receive a rivet 23 which passes through the plates 12 and pivotally mounts the member 20 thereon. This member 20 is adapted to engage the door A, as will be later described, and may be called a pressure head.

It will be noted that the extremities of the plates 12 are arranged to engage the inner surfaces of the plate 16 and bight 21 of the members 14 and 20 respectively, and these ends, designated at 24 and 25, thus act as stop means to limit swinging movements of said members about their pivots 18 and 23. The ends 24 and 25 of the plates are, however, rounded off, as designated respectively at 26 and 27, in such manner as to permit oscillating movements of the members 14 and 20 in a downward direction only, and as shown in Fig. 2, it will be noted that in their normal positions the members stand in such relation to each other that the respective door post and door engaging surfaces of the angles 15 and bight 21 stand in a common vertical plane.

The upper member 14 is provided with a pin 28 welded rigidly to the center of the plate 16 and extending inwardly between the plates 12 above the rivet 18. The free extremity of the pin 28 is formed with an eye 29 to which one end of a retractile coil spring 30 is attached, the other end of the spring being connected to a rivet 31, as clearly indicated in Fig. 2. The spring 30 thus acts to yieldably resist downward swinging movements of the member 14 and to hold it against the stop means 24, as clearly shown in Fig. 2. The lower member 20 is provided with a loop 32 secured to its bight 21 above the pivot 23 and a retractile coil spring 33 is connected at one end by means of a link 34 to said loop 32, the other end of the spring being attached to rivets 35 extending through the plates 12. The spring 33 thus acts in a similar fashion to yieldably resist downward swinging movements of the member 20 and to hold it against its stop 25. Between the members 14 and 20 the plates 12 are cut away, as indicated at 36, to provide clearance for the downward swinging movements of the upper member 14. In operation the implement has one of its hooks 19 engaged with the door post D, with the handle 10 of the implement disposed horizontally in what may be called a starting position. The bight 21 of the lower member 20 will then engage the door A immediately inward of the post. The handle 10 may then be forced downwardly and the hook 19 engaged with the post will act as a fulcrum about which considerable pressure may be brought to bear to the lower member 20 inwardly upon the door. The leverage is such that the door A will thus be forced inwardly, as indicated in Fig. 3, drawing

the nails E from the post. It will be apparent that the oppositely projecting hooks 19 render the implement usable with equal convenience at either end of the door A, the hook on one side being engaged with the post on that side, and the hook at the other side being then so disposed as to properly engage the other post when the implement is shifted to the other end of the door. The aforesaid location of the members 14 and 20 with their door post and door engaging surfaces normally in a common vertical plane insures that these surfaces will properly engage the parts when the implement is held horizontally and brought into engagement with the posts and door, as previously described.

As the handle 10 is forced downwardly to bring the prying pressure upon the door A, the members 14 and 20 may, as clearly shown in Fig. 3, oscillate about their pivots to assume the necessary relatively angular positions and keep them in flat bearing engagement with the post D and the door. Thus any tendency of these parts to cut into the post or door is eliminated and no marring or damage results, such as is the case with make-shift implements now used for this purpose. Of course, when the implement is removed from the door the springs 30 and 33 immediately return the members 12 and 20 to their starting positions, ready for the next operation.

It will be noted that continuation of the downward swinging movement of the handle 10 from the position of Fig. 3 will result in an upward movement of the door, since the pivot 23 for lower member 20 is at a fixed distance from the pivot 18 about which the implement as a whole swings, and the pivot 23 will have an upward component of movement as the operation proceeds. Such upward movement of the lower member 20 and the door A may be relatively small but it is important in that in some doors of well known form lower nails (not here shown) are used which engage only in downwardly opening notches in the lower edges of the door. A comparatively small upward movement of the door is all that is required to free the notches from these lower nails.

It is understood that suitable modifications may be made in the structures disclosed, provided that such modifications lie within the spirit and scope of the appended claims.

Having now, therefore, fully disclosed my invention, what I claim to be new and desire to secure by Letters Patent is:

1. An implement for prying a grain car door inwardly at either end away from the door post, comprising in combination, a handle, a pair of bracket plates secured to one end of the handle and extending therebeyond, upper and lower members pivotally attached in spaced relation to the said bracket plates, the upper member having oppositely projecting fingers for selective engagement with the inner sides of the door posts, the lower member having a surface disposed centrally and below said fingers for engagement with the outer surface of the door, stop means on the bracket plates engaging said members and restraining them against oscillating movements in one direction about their pivots so that the respective door post and door engaging surfaces of the members normally stand in alignment, and separate spring means connected between the respective members and the bracket plates and yieldably holding said members against said stop means.

2. An implement for prying a grain car door inwardly at either end away from the door posts,

comprising in combination, a handle, a pair of bracket plates secured to one end of the handle and extending therebeyond, upper and lower members pivotally attached in spaced relation to the said bracket plates, the upper member having oppositely projecting fingers for selective engagement with the inner sides of the door posts, the lower member having a surface disposed centrally and below said fingers for engagement with the outer surface of the door, stop means on the bracket plates engaging said members and restraining them against oscillating movements in one direction about their pivots so that the respective door post and door engaging surfaces of the members normally stand in alignment, and separate springs connected between the respective members and at least one of the bracket plates for normally holding the members against the stop means, the said springs being positioned between and protected by the bracket plates.

3. An implement for prying a grain car door inwardly at either end away from the door post, comprising in combination, a handle, a pair of bracket plates secured to one end of the handle and extending therebeyond, the said plates hav-

ing upper corner portions and lower corner portions separated by an intervening notch, an upper prying member pivotally connected to the upper corner portions of the bracket plates and swingable downwardly into said notch in the operation of the implement, a lower prying member pivoted to the lower corner portions of the bracket plates and swingable downwardly with respect thereto, and separate springs connected between the upper and lower prying members and the bracket plates and yieldably restraining them against downward swinging movements.
